UNITED STATES PATENT OFFICE.

GEORGE T. TURNER, OF PHILADELPHIA, PENNSYLVANIA.

DESIGN FOR AN AUTOMOBILE-FRAME.

SPECIFICATION forming part of Design No. 35,713, dated February 11, 1902.

Application filed January 2, 1902. Serial No. 88,253. Term of patent 7 years.

To all whom it may concern:

Be it known that I, GEORGE T. TURNER, a citizen of the United States of America, and a resident of Philadelphia, Pennsylvania, have invented and produced a new and original Design for an Automobile-Frame, of which the following is a specification.

As shown in the drawing, the leading or characteristic feature of my design consists in the shape or configuration of a compound skeleton frame A B, composed of longitudinal members *a*, struts *b*, a steering-head *c*, and cross-bars *d*, together with rearward uprights *e*, connected by a cross-bar *f*, extending rear-

wardly from the two frames, and forming a component part thereof are shaped members *g*, arranged in pairs, as illustrated.

What I claim as new, and desire to secure by Letters Patent, is—

The design for an automobile-frame substantially as herein shown and described.

Signed at Philadelphia this 25th day of January, 1901.

GEORGE T. TURNER.
